SAFETY RAZOR

Joseph Muros, Astoria, N. Y., assignor to Gillette Safety Razor Company, Boston, Mass., a corporation of Delaware

Application April 10, 1931, Serial No. 529,154

10 Claims. (Cl. 30—12)

Some safety razors comprise blade-clamping members, such as a guard member and a cap or blade-backing member, with means to cause said members to clamp a member between them. In 5 some of such razors the guard member is provided with projections to enter positioning apertures in the blades.

An object of my invention is to provide means co-operative with one of the blade clamping members and with a blade to position said blade in 10 shaving relation to the guard member in the event that such blade is provided with a positioning aperture that does not accurately fit the projections from the guard member to position the blade 15 in shaving position thereon.

In carrying out my invention I provide an adapter provided with an aperture to properly engage or fit and receive the projections from one or both of the clamping members, said adapter 20 having projections to co-operate with a blade to position the latter upon the guard member in shaving relation thereto, said adapter being arranged between or to fit between said members in such a way as not to interfere with proper 25 positioning and curving of the blade between the clamping members.

My invention also comprises novel details of improvement more fully hereafter set forth and then pointed out in the claims.

Reference is to be had in the accompanying 30 drawing, wherein—

Figure 1 is a side view of a safety razor embodying my invention. Fig. 2 is a cross section on line 2—2 in Fig. 1. Fig. 3 is a detail perspective 35 view of my improved adapter. Fig. 4 is a plan view illustrating a position a blade may take upon the guard member in the event that the blade-positioning aperture does not fit the projections on the guard member, and Fig. 5 is a partly broken 40 plan view of parts assembled for use.

Similar numerals indicate corresponding parts in the several views.

The numeral 1 indicates a guard member and 45 2 indicates a cap or blade-backing member adapted to clamp a blade 3 therebetween for shaving. Any suitable or desired means may be provided for detachably connecting the members 1 and 2. I have illustrated the cap 2 provided with a threaded stem 4 adapted to pass through the guard member and enter the threaded recess 5a in a handle 5, in a well-known way, for detachably clamping the members 1 and 2 against the blade.

The guard member 1 is shown provided with 55 spaced projections 6 adapted to enter a blade positioning aperture 3a in the blade, shown in the form of a longitudinal slot, the cap 2 being shown provided with recesses 7 adapted to receive the projections 6. The cap 2 is shown provided 60 with a substantially centrally disposed projection

8 adapted to pass through the aperture 3a of the blade and to enter a recess 9 in the guard member. The projections 6 and 8 are shown in non-circular form and are disposed in substantial alignment when the cap and guard are assembled 65 in shaving relation. The projections are normally adapted to receive a blade positioning aperture in a blade substantially corresponding in outline or contour to the general outline of the collective group of the projections whereby the blade 70 will be retained in shaving position between the clamping members 1 and 2 when the latter are clamped together against the blade.

In order to enable the members 1 and 2 to properly retain a blade in shaving position between them in the event that such blade is provided with an aperture that is not adapted to so receive the projections 6 and 8 as to properly retain the blade in shaving position, I provide an adapter 10, preferably comprising a relatively 80 thin plate or piece of metal, having a blade positioning aperture 11 adapted properly to receive, engage and co-operate with the projections 6 of the guard and the projection 8 of the cap, to retain the adapter from displacement, said 85 adapter being arranged between or to fit between the clamping members in the position that would be assumed by a blade properly apertured to fit said projections. The adapter 10 is relatively narrow with respect to the width of the blade so 90 as not to interfere with the proper flexing of the blade when clamped between the members 1 and 2, as illustrated in Fig. 1. The adapter 10 is provided at its ends with outwardly or upwardly extending projections 12 adapted to receive 95 notches or recesses 13 in the ends of the blade to retain the latter in shaving position with respect to the members 1 and 2. The projections 12 of the adapter 10 are shown located in longitudinal alignment with the aperture or slot 11 100 and spaced from the ends thereof. The adapter and the recesses 13 of the blade are shown located in longitudinal alignment with the aperture or slot 3a of the blade, the arrangement being such that when the adapter is in position on the guard member the blade may be fitted to the adapter in any position in which the blade may be applied on the adapter.

A blade having a large aperture or slot 3a that is not adapted to engage but merely to receive the projections 6 but not to position or align the blade in shaving relation on the guard is illustrated in Fig. 4, from which it will be understood that the blade may assume various angular or edgewise positions with respect to the 115 guard member. When, however, the adapter 10 is placed upon the guard member and the aperture or slot 11 properly receives the projections 6 of the guard member, said adapter will be retained in a proper position so that when the 120

blade 3 is placed against the adapter and the projections 12 of the adapter enter the recesses 13 of the blade, the latter will be retained by the adapter in proper shaving position on the guard member. The projection 8 from the cap 2 also by properly engaging or fitting the aperture 11 of the adapter causes the cap to be retained by the adapter in proper shaving position.

The inner surface 14 of the cap 2 is shown having a curvature which is sufficient to admit the blade and the adapter in position between the guard member and the cap member to permit said members to be properly clamped against the blade for retaining the same in shaving position without interference by the adapter, which is thin enough not to interfere with the clamping action of the parts.

In the preferred form of the invention all of the aligning means or positioning means including the apertures or slots 3a and 11, the projections 6 and 8, as well as the ears 12 and recesses 13 are located preferably in the central zone of their respective elements and the longitudinal central portion of the razor head.

In view of the fact that the alignment between the adapter and cap and between the adapter and guard is mutual then it is self-evident that the adapter is directly engaged by the lug 8 of the cap and the lugs 6 of the guard whereby the cap and guard are aligned through the medium of the adapter. Furthermore, it may be accurately stated that the adapter is aligned with the cap and guard by the projections on the cap and guard. In the invention as disclosed there is no direct mutual engagement between the cap and guard for aligning purposes. It is contemplated however that the blade and adapter should be applicable to types or kinds of razors in which there is direct aligning engagement between the cap and guard.

Having now described my invention, what I claim is:—

1. A safety razor comprising a head and a handle, said head including a cap, a guard, an apertured adapter and a blade having a large aperture, said cap having a positioning projection extending through the blade and adapter and engaging the latter, said projection extending toward the guard but spaced from the guard and blade, said guard having a projection also extending through the blade and adapter and engaging the latter but spaced from the blade and the cap, said projections being arranged in spaced relation whereby the cap and guard are aligned by the projections and the co-acting adapter, said adapter having projections engaging and positioning the blade, and co-acting means on said cap and handle to clamp the parts together.

2. A safety razor according to claim 1 in which the projections are arranged in longitudinal alignment with reference to each other and the razor head.

3. A safety razor according to claim 1 in which the projections of the cap, guard and adapter are located in the central longitudinal portion of the razor head.

4. A safety razor comprising a head and a handle, said head including cap and guard members, an apertured adapter and a flexible blade having a large aperture and positioning means, said members having co-acting blade-shaping faces, projections extending in spaced opposed relation from said faces and engaging the adapter to align the members by co-operation of the pro-

jections with the adapter, projections on the adapter engaging the positioning means on the blade to align the same with the cap and guard, said second-named projections located in spaced relation from the first-named projections, all of said projections being in longitudinal alignment and co-acting means on the cap and handle to draw and clamp the parts together in shaving relation.

5. A safety razor according to claim 4 in which the ends of the adapter are provided with projections, and the ends of the blade are provided with ears, said projections engaging said ears to align the blade with the cap and guard.

6. A safety razor comprising a head and a handle, said head including a cap and a guard, a blade having a cutting edge, and an adapter, said blade being provided with a slot or aperture so large that it will receive in spaced relation therefrom conventional cap and guard projections, said slot being substantially as wide as one third the width of the blade, said slot having a continuous uninterrupted outline, said blade having positioning ears on its ends, said adapter having an aperture and positioning means to engage the ears of the blade, means on the cap and guard to locate and align the adapter with the cap and guard, and means on the cap and handle to clamp the parts together.

7. A safety razor having a cap, a guard, an adapter and a blade, said adapter and blade having longitudinally and centrally located slots, interengaging means on said cap, guard and adapter to align the same, said blade having locating means on the ends thereof beyond the slot and in alignment therewith and said adapter having means in alignment with the slot and at the extremities thereof engaging the locating means of the blade to align the blade with the guard, and means to clamp the parts together.

8. A thin flexible double-edged safety razor blade having a central longitudinal slot of a width exceeding the thickness and length of the usual blade positioning means of the razor on which it is to be used so that such positioning means may pass freely through the slot without aligning the blade with the razor elements, said blade being provided with a recess in each end thereof beyond said slot forming blade-positioning ears, said recesses being located in the longitudinal axis of said slot and adapted completely to locate the blade in shaving position.

9. A blade adapter for a safety razor of the type wherein a blade is interposed between two clamping members which are both provided with projecting aligning means, said adapter comprising a plate member having a central longitudinal slot fitting the aligning means of both clamping members, and blade engaging and positioning means located in the longitudinal axis of said plate at the ends thereof and remote from the ends of said slot.

10. A blade adapter for a safety razor of the type wherein a blade is interposed between two clamping members both having blade-locating projections thereon, said adapter comprising a plate member having a central longitudinal slot adapted to engage the projections on both of said clamping members and thereby align said members, and blade engaging and positioning projections in the longitudinal axis of said plate member at the ends thereof and spaced beyond the ends of the slot.

JOSEPH MUROS.
